Attorney

UNITED STATES PATENT OFFICE.

JOHN M. PERRY, OF VOSBURG, MISSISSIPPI.

CHECK-CONTROLLED MECHANISM.

Application filed August 10, 1926. Serial No. 128,446.

This invention relates to coin or check mechanisms, and particularly to such mechanisms as are associated with vending machines.

5 One object of the invention is to provide a mechanism, controlled by the deposit of a coin or check, which will operate a detent shaft to move a display device, for the purpose of exposing articles in succession.

10 Another object is to provide means for preventing retrograde movement of an operating rod, when forward movement has begun, and means for releasing the first means upon completion of the forward 15 movement of the rod, whereby to permit the parts to resume normal position.

Other objects and advantages will be apparent from the following description when taken in connection with the accompanying 20 drawings.

In the drawings:

Figure 1 is an elevation of the mechanism, in normal position, and with a coin in proper position for operating the detent 25 shaft.

Figure 2 is an elevation of the parts when the operating rod has been pulled out, and the detent shaft has been rocked.

Figure 3 is a horizontal sectional view on the line 3—3 of Figure 1.

Figure 4 is a vertical sectional view on the line 4—4 of Figure 1.

Referring particularly to the accompanying drawings, 10 represents a base through 35 which is disposed one end of a shaft 11, which is adapted to operate detents, not shown, for actuating an article displaying means, such displaying means being illustrated in my Patent #1,556,541, issued October 6, 1925, and in which patent is also 40 shown the detents of the shaft 11.

Secured on said end of the shaft 11 is a 45 radially extending arm 12, the outer end of which is provided with a nose 13, to which reference will be made later herein. A brace 14 is mounted on the base, and secured at its opposite ends to the arm 12, and to the brace, is a coil spring 15, which normally urges the arm 12 upwardly to rock the shaft 50 11 in such position that the detents will hold the display means against movement.

Pivotedly mounted on the base, adjacent the nose of the arm 12, is a rockable member 16, the upper portion of which is formed 55 with a coin or check receiving notch or re-

cess 17, such recess opening in the direction of the said nose, whereby to permit the coin or check to engage with said nose. The upper end of the member 16 is formed with hook portion 18, overlying the adjacent end 60 of a pivoted pawl 19, while its lower end is pivotally connected with the adjacent end of a link 20. A coil spring 19' is connected to the upper end of the pawl 19 and to a pin 10', on the said base, for normally urging 65 the pawl toward the teeth of the link 20. Pivotedly mounted on the base, and intermediately pivoted to the link 20, is an upwardly extending arm 21, the portion of the said arm 21, immediately above its pivot, 70 being properly held by the guide 22. To the upper end of the arm 21 there is connected an operating rod 23, having a terminal hand loop 24, which is adapted to be grasped to pull the rod, and cause the rocking of the 75 arm 21. The upper edge of the link 20 is formed with ratchet teeth 25, which are engaged by the before-mentioned pawl 19. A coil spring 26 is connected, at one end, to the ratchet link 20, and at its other end to 80 a bracket 27, secured to the base 10, for the purpose of normally urging the link in one direction, whereby to cause the hook of the member 16 to rock the pawl 19 out of engagement with the teeth of the link. 85

Disposed in an inclined position on the upper portion of the base 10 is the coin or check chute 28, the lower end of which is disposed in position to deposit a coin or check in the notch of the member 16, while 90 the upper end is provided with a coin or check receiving slot 29. The lower end of the chute is also disposed in close relation to the nose of the arm 12, whereby the coin or check is held within the notch or recess, 95 and partially resting against the said nose. The pawl 19 is normally spring pressed into engagement with the teeth of the link 20.

Pivotedly mounted on the base, inwardly of the lower end of the chute 28, is an ar- 100 cuate member 30, one end of which is provided with a laterally directed foot 31, normally engaged by the arm 12, to rock said member and press its other end, which is provided with a similar foot 32, downwardly against the inner end of the pawl 19, 105 whereby to rock the pawl and maintain its nose out of engagement with the teeth 25. This permits the free outward movement of the link 20, when the lever 21 is swung out. 110

wardly, without accomplishing any operation of the parts of the device, should no coin be deposited in the machine.

When a coin is deposited in the upper end of the chute, such coin will slide down the chute until it enters the notch of the member 16, and rests against the nose of the arm 12. Upon pulling outwardly on the rod 23, the arm 21 will be rocked on its pivot, causing the link 20 to be drawn therewith, which in turn causes the member 16 to be rocked, with the result that the coin or check moves the arm 12, to rock the shaft 11. As the shaft 11 is rocked, the arcuate member 30 is released from the arm 12, whereupon the spring 19 rocks the pawl so as to engage its nose with the teeth 25, and at the same time move the adjacent end of the arcuate member 30 upwardly until said member is stopped by the pin 10. When the link 20 has moved to the limit of its stroke, the coin will have wiped past the nose of the arm 12 and fallen from the notch or recess, into a box 33, disposed to receive it, whereupon the arm 12 is free to be restored to normal position by its spring 15. When the arm 12 has moved upwardly it engages with the foot 31, of the arcuate member, rocking said member so that its other foot 32 depresses the adjacent end of the pawl 19, and holds the nose of the latter elevated out of engagement with the teeth of the link 20. The spring 26 restores the rod 23, the arm 21, and the rocker 16, to normal position, whereby the latter presents its coin notch in position beneath the coin chute, to receive a coin.

Attention is directed to the fact that, after having deposited a coin in the chute, and such coin has passed into the recess of the member 16, an outward pull on the rod 23 causes the entire operation of the device, and the restoration of the arm 12, and the shaft 11, to normal position, without releasing the rod 23. Upon releasing the rod 23, the remainder of the parts assume their normal position.

What is claimed is:

1. The combination with a shaft, of a check controlled operating means therefor including an arm on the shaft, a check receiving rockable member, means for rocking the member to engage the check with said arm to move said arm and rock said shaft, means for preventing premature retrograde movement of the rocking means, and means operable by the said arm upon assuming nor-

mal position for releasing the preventing means upon completion of the stroke of said rockable member.

2. The combination with a shaft having a radial arm thereon, a rockable member having a recess for the reception of a check and arranged to be rocked to engage the check with the arm to rock the arm and shaft, means for rocking the rockable member including a toothed member, a spring urged detent normally out of engagement with the toothed member, a rock arm engaged at one end with the detent and having its other end engaged by said radial arm whereby to rock the detent out of engagement with the toothed member and movable by said detent upon movement of said arm away therefrom.

3. The combination with a shaft having a radial arm thereon, of a check controlled operating mechanism for said arm and shaft including a rockable member having a check receiving recess and arranged in position to engage a check with said arm to move the latter and rock the shaft, an operating means connected with the rockable member and including a toothed link, a detent normally urged toward engagement with the teeth of the link and normally held from such engagement, and means disposed in position to be engaged and rocked by the said arm upon movement of the arm toward normal position to disengage the detent from the link, said last-named means being rocked in the opposite direction by the detent upon movement of said arm away from said means.

4. The combination with a rock shaft having a radial arm thereon, of a rockable member having a check receiving recess and disposed in position to engage the check with said arm, an operating arm, a toothed link operatively connected with the operating arm and the rockable member, a detent for engagement with the toothed link, said detent being normally out of engagement with the link, and an arcuate member having one end disposed in the path of the said arm to be engaged and rocked thereby upon movement of the arm toward normal position, the other end of said arcuate member being arranged to engage the said detent, to rock the same out of engagement with the link upon such engagement by said arm.

In testimony whereof, I affix my signature.

JOHN M. PERRY
